UNITED STATES PATENT OFFICE.

FREDERICK MESINGER, OF NEW YORK, N. Y., ASSIGNOR TO THE MESINGER BICYCLE SADDLE COMPANY, OF SAME PLACE.

DESIGN FOR A BICYCLE-SADDLE.

SPECIFICATION forming part of Design No. 26,344, dated November 24, 1896.

Application filed October 12, 1896. Serial No. 608,661. Term of patent 7 years.

To all whom it may concern:

Be it known that I, FREDERICK MESINGER, a subject of the Emperor of Germany, residing in the city, county, and State of New York, have invented and produced a new and original Design for Bicycle-Saddles, of which the following is a specification, reference being had to the accompanying drawings, showing a part thereof.

10 Figure 1 is a plan view of a saddle, showing my design; and Fig. 2 is a cross-sectional view of the same on line xx of Fig. 1, these two views being deemed necessary to fully illustrate said design.

15 The leading features of my design consist, in brief, of an outline of general pelecoidal shape having a centrally-disposed opening, the field within said opening being crossed by longitudinal and transverse lines, substantially as in Fig. 1 of the annexed drawings. Said central opening is bordered and indicated by lines that begin near the pommel

end of the saddle and extend in gradually-diverging sinuous lines a toward the rear of the saddle, finally approaching each other, 25 and terminating in an angle b directly opposite the starting-point.

The letter c indicates that portion of my design corresponding to the rear end of the saddle, the same being semioval, and from 30 the extreme ends of said semioval portion inwardly-curved lines dd extend forward, gradually approaching each other, being finally connected by a substantially semicircular line e at the pommel end of the saddle design. The 35 side walls of the said design extend upward and curve inward, as in Fig. 2.

What I claim is—

The design for a bicycle-saddle substantially as herein shown and described.

FREDERICK MESINGER.
